UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF WEST VIRGINIA.

OIL-PUMP.

No. 904,484.

Specification of Letters Patent.

Patented Nov. 17, 1908.

Application filed March 23, 1907. Serial No. 364,142.

To all whom it may concern:

Be it known that I, RUSSELL HUFF, a citizen of the United States; and resident of Detroit, county of Wayne, State of Michigan, have invented certain new and useful Improvements in Oil-Pumps, of which the following is a specification.

The present invention relates to improvements in oil pumps, especially adapted for use with motor vehicles, and will be described in connection with the accompanying drawings, in which—

Figure 1 is a vertical sectional view through a pump constructed in accordance with the present invention. Figs. 2 and 3 are, respectively, transverse sections through one of the pump barrels and the connecting rod between the pump plungers and driving shaft. Fig. 4 is a plan view partly in section. Fig. 5 is a detail view of one of the valves.

Referring to the drawings, 1 designates the body of the pump within which are formed two barrels or chambers 2, each communicating with supply ducts 3 and discharge ducts 4, said ducts communicating through valve controlled passages with couplings 5, 6, for supply and feed pipes.

The shaft 7 is mounted in suitable bearings in the pump body 1, and provided at one end with a worm wheel 8 which engages a suitable worm 9 on a shaft 10 geared to the driving or propelling mechanism of the vehicle in the ordinary manner.

The plungers 11 extend above the body 1, and the upper portion of each is externally threaded as at 12 and provided with a longitudinal slot 13. Into said slots 13 in the plungers 11 project the ends of a pin 14 which is detachably connected with the upper end of a rod 15, the lower end of which engages an eccentrically mounted pin 16 on the shaft 7. The pin 14 is preferably provided with an intermediate section 17 polygonal in cross section, which fits in a correspondingly shaped passage in the rod 15, and said pin and rod are connected by a key or cotter pin 18. The connecting rod 15 is guided and held from lateral motion toward either plunger 11 by walls of the slot in the body 1 through which it moves and the end of the eccentric pin 16 bears against a smooth surface formed on said body. The length of

the slot 13 is readily varied by adjusting a sleeve 19, which has an internal thread engaging the threaded section 12 of the plunger, and said sleeve is held in any desired adjusted position by a clamping bolt 20 which is screwed therein and provided at its inner end with a tapering portion 21 adapted to fit the correspondingly tapered seat formed at the upper end of the plunger, whereby when said pin is screwed into the sleeve and caused to bear against said seat the upper end of the plunger is held in close engagement with the sleeve 19. Said sleeves 19 are guided by suitable passages in a cap or cover 22 detachably connected with the pump body 1, as by screws.

It has been found that pumps of this type should be provided with a stuffing box at the upper end of the pump barrel, even if the parts are made with the greatest care and accuracy. By the present invention such stuffing box is provided by a gland 23 screwed into the upper end of the pump barrel, and said gland is held securely in place by the engagement between inwardly extending projections 24 on the cap or cover 22 and the projecting head or end of the gland. Preferably said projecting head or end 25 is made polygonal in cross section, and the projections 24 are so positioned that said head is engaged on opposite sides, whereby it is effectually held from turning when the cap 22 is in position on the body 1.

The valves controlling the passage of oil to and from the pump barrels have been specially designed in order to prevent any leakage. As shown, the valves each comprise a ball 26 held against a suitable seat by a spring 27. The seat is made in the form of a tubular member 28 which is screwed into the body 1 and provided with suitable passages and a circumferential groove 28^a adapted to register with the oil ducts. Said seats are held in position by lock nuts 29 and closed at their outer ends by plugs 30 against which the springs 27 bear.

Gaskets 31, 32 and 33, of soft material, such as lead, are arranged between the inner ends of the valve seats and the pump body, between the lock nuts 29 and said body, and between the plugs 30 and the outer ends of the valve seats. This construction positively

prevents any leakage of oil backward around the balls 26, or leakage at any other point about the valve.

The operation of the pump will be readily understood from the foregoing description. It will be seen that by connecting the rod 15 with the pump plungers through the pin 14 which is detachably connected with said rod it is possible to readily remove either pump 10 plunger from the pump without disconnecting the other, or if desired the rod 15 may be removed without affecting either of the plungers. The friction of the worm gear holds the eccentric pin 16 against the machined face of the body 1; but to prevent any possibility of the shaft being withdrawn from the pump body, by accidentally rotating the driving gear in a reverse direction, and for convenience in handling the pump 20 when removed from the vehicle, a pin 34 is preferably employed, such pin extending into a suitable groove in the shaft, as shown in Fig. 1.

Having thus described, the invention, 25 what is claimed is:

1. In an oil pump, the combination of a plunger having a longitudinal slot extending through its outer end, a sleeve adjustable on the plunger to vary the length of 30 the slot therein, and means extending into said slot and adapted to reciprocate the plunger.

2. In an oil pump, the combination of a plunger having its outer end threaded and 35 provided with a longitudinal slot, a sleeve engaging the threaded section of the plunger and a adjustable longitudinally thereof, means for locking the sleeve to the plunger, and means for reciprocating the plunger having 40 a pin or stud extending into said slot.

3. In an oil pump, the combination of a plunger having its outer end threaded and provided with a longitudinal slot, an internally threaded sleeve on the threaded section 45 of the plunger and adapted to vary the length of said slot, a clamp or lock pin extending through said sleeve and into engagement with the plunger to hold the sleeve stationary in any adjusted position, and 50 means for reciprocating the plunger including a pin or stud extending into said slot.

4. In an oil pump, the combination of a relatively stationary body having the pump barrel formed therein, a plunger extending 55 into the barrel, a gland secured within the open end of the barrel, a guide for the plunger detachably connected with the pump body and engaging said gland, and means for reciprocating the plunger.

60 5. In an oil pump, the combination of a relatively stationary body having the pump barrel formed therein, a plunger extending into the barrel, a gland secured within the open end of the barrel, a hollow cap detachably connected with the body and suit-

ably formed internally to lock the gland against rotation, said cap also constituting a guide for the plunger, and means for reciprocating the plunger.

6. In an oil pump, the combination of a 70 body having the pump barrel formed therein, a plunger extending into the barrel, a gland having a threaded section screwed into the open end of the pump barrel, the portion of said gland that projects from 75 the pump barrel being polygonal in cross section, a hollow cap detachably connected with the body and engaging said projecting portion of the gland, and means for reciprocating the plunger. 80

7. In an oil pump, the combination of a relatively stationary body having two pump barrels formed therein, plungers extending into said barrels and each provided beyond its barrel with a longitudinal slot, a shaft 85 mounted in said body, a rod connected with the shaft to be reciprocated thereby, a pin carried by said rod and extending into the slots in the plungers, a gland screwed into the open end of each pump barrel, and a 90 hollow cap detachably connected with the body and provided with guides for the plungers and with means for engaging said glands.

8. In an oil pump, the combination of a 95 body having two pump barrels and suitable supply and discharge ducts formed therein, plungers extending into said barrels, a shaft, a rod arranged within a slot in the body and having one end eccentrically connected with 100 the shaft and its other end extending between the plungers, the walls of said slot preventing lateral movement of the rod toward either plunger and a pin detachably connected with said rod and engaging the 105 plungers to communicate reciprocating motion thereto.

9. In an oil pump, the combination with a body having a pump barrel and suitable supply and discharge ducts formed therein, 110 a plunger extending into the barrel, and means for reciprocating the plunger, of check valves controlling the flow of oil to and from the pump barrel and each comprising a tubular seat which is screwed into 115 a suitable socket in the body and provided with openings communicating with ducts in said body, a ball within said seat, a lock nut for holding the seat in position on the body, and soft metal gaskets arranged between the valve seat and body and between the lock nut and body, substantially as and for the purpose described. 120

10. In an oil pump, the combination with a body having a pump barrel and suitable 125 supply and discharge ducts formed therein, a plunger extending into the barrel, and means for reciprocating the plunger, of check valves controlling the flow of oil to and from the pump barrel and each com- 130

prising a tubular seat which is screwed into a suitable socket in the body and provided with openings communicating with ducts in said body, a ball within said seat, a lock nut for holding the seat in position on the body, a plug closing the outer end of the valve seat, a spring between said plug and ball, and soft metal gaskets arranged respectively between the valve seat and body, the lock

nut and body, and the plug and valve seat, to substantially as and for the purpose described.

In testimony whereof I affix my signature in presence of two witnesses.
